SHOOTING PRACTICE DUMMY GUN

Filed Aug. 5, 1920

2 Sheets-Sheet 2

UNITED STATES PATENT OFFICE.

ROBERT EDWIN REARDON, OF WASHINGTON, DISTRICT OF COLUMBIA.

SHOOTING-PRACTICE DUMMY GUN.

Application filed August 5, 1920. Serial No. 401,419.

To all whom it may concern:

Be it known that I, ROBERT EDWIN REARDON, a subject of the King of Great Britain, residing in the city of Washington, District 5 of Columbia, United States of America, have invented a new and useful Improvement in Shooting-Practice Dummy Guns, of which the following is a specification.

This invention is a development of the 10 subject of my United States Patent Number 1,382,120, for new and useful improvements in dummy practice rifles, and relates to further improvements in imitation or dummy rifles affording training in accuracy 15 rate shooting. The object of this invention is to enlarge the field of usefulness of such devices for cadet, school and home training, by simplifying construction, lessening cost of manufacture, while maintaining 20 or increasing operating accuracy, and providing simple and safe new means of using dummy cartridges with shooting practice dummy guns to add interest and instructiveness by simulation of loading and 25 ejection actions.

With these objects in view the invention consists in the arrangement, construction and combination of parts hereinafter described and particularly pointed out in the 30 claims, it being understood that I do not limit myself to the details of construction of the several parts.

The invention is illustrated in the accompanying drawings in which Figure 1 is a 35 vertical, centrally longitudinal, operating-part-sectional view of a simple cartridgeless form of my shooting practice dummy gun.

Figure 2 is a vertical, centrally longitudinal, operating-part-sectional view of a 40 simple single loading dummy cartridge using form of my shooting practice dummy gun.

Figure 3 is a vertical, centrally longitudinal, operating-part-sectional view of a 45 more military type of single loading dummy cartridge using form of my shooting practice dummy gun.

Figure 4 is an enlarged, vertical, centrally longitudinal, sectional view of the 50 dummy cartridge receiving and ejecting mechanism of the simple dummy cartridge using form of my shooting practice dummy gun shown in Figure 2.

Figure 5 is a perspective view, from the 55 right upper rear end, of the bolt sleeve with

manipulating arm and locking lug which encases the hammer plunger in the military simulating form of my shooting practice dummy gun shown in Figure 3. 60

Figure 6 is a side elevation in enlargement of the hammer type of flat tip shown on the core rod in the barrel of my shooting practice dummy gun in Figures 1, 2 and 3.

Figure 7 is a side elevation showing, 65 in a vertical, centrally longitudinal section of barrel muzzle of a dummy gun, my ink pad means of inking the tip of the core rod in the barrel of a dummy practice rifle, which may be used in combination with my 70 improved shooting practice dummy gun. This modification is shown and described in my aforementioned United States patent on this subject and only included herewith for illustration of possible combination. 75

Figure 8 is a side elevation of my pencil lead holding modification of the form of tip usable on the core rod in the barrel of my improved shooting practice dummy gun for marking the target. This modification 80 is shown and described in my aforementioned United States patent on this subject, and only included herewith for illustration of possible combination.

Figure 9 is a side elevation showing in 85 vertical, centrally longitudinal section my improved, resiliently mounted, capsule bullet form of ink fountain tip usable on the core rod in the barrel of my shooting practice dummy gun for marking the target. 90

In the drawings like numbers refer to similar parts.

The gun body is designated by the numeral 1. Incorporated in the gun body in the simple cartridgeless form of my shooting practice dummy gun shown in Figure 1, are: a target hitting barrel core rod 2; a hammer plunger rod 3; a hammer plunger arresting and releasing trigger 4 with a nose 21 adapted to interpose space between the hammer plunger face and the butt of the barrel core rod when operating to arrest the hammer plunger; a trigger pivot 4^B; a foresight-muzzle-band piece 5; a rearsight-breechstop piece 6, through an aperture in which the hammer plunger rod has limited rearward sliding movement, shown as a separate part for convenience of manufacture but otherwise integral with the gun body; a forward barrel core rod stop bushing 7, shown as pinned by pin 7^a in separate part for convenience 100 105 110

of manufacture but otherwise integral with the gun body; a barrel core rod butt piece 8 and hammer plunger rod head piece 9, respectively shown as separate parts for convenience of manufacture but otherwise integral with the parts to which they are attached; a barrel core rod retracting spring 10; a hammer plunger rod advancing spring 11; a hammer plunger rod stop-knob 12; a trigger spring 13; a foresight-muzzleband attaching screw 14; a rearsight-breechstop piece attaching screw 15. The barrel core rod 2 is shown in Figures 1, 2, 3 and 6 with a flat, or hammer, tip 33, which may be replaced by other forms of tip, particularly such as shown in Figures 7, 8 and 9.

In the simple dummy cartridge using modification of my shooting practice dummy gun shown in Figures 2 and 4, the part designated by numeral 8, namely the butt enlargement of the barrel core rod, 2, is constructed with a trough 16 in it, formed as a rearwardly extending semi-cylindrical pan with a ridge terminal butt 20 and having lying in the bottom of the said trough 16 a tiltable longitudinal plate 17 loosely pivoted at the butt end having thereat a tilting tip 18 projecting downwardly below the trough bottom into the path of a tripper 19 and adapted to engage same and tilt the trough plate 17 when the barrel core rod 2 is retiring. The tripper 19 is pivotally mounted 19^A in such manner as to not impede forward movement of the barrel core rod 2. An aperture 16^A in the gun body 1 above normal position of the trough 16 permits a dummy cartridge 22 to be inserted in the said trough. A stud 25 on the under side of the troughed core rod butt 8 engages a longitudinal groove 25^A in the barrel bore of the gun body 1, thus maintaining the cartridge trough 16 always facing towards the cartridge loading aperture side of the barrel bore of the gun body. The trigger 4 in this modification of my shooting practice drill gun may be constructed with an approximately squared nose 21 which thus acts to arrest the hammer plunger 9 when retreated, stops retreat of barrel core rod butt against the hammer plunger 9, when gun is cocked and may also be made instrumental in the ejection through the loading aperture 16^A of the dummy cartridge 22 by the tilting plate 17, by abutting, as the barrel core rod 2 retreats after firing action, the lower edge of the dummy cartridge head, which projects rearwardly beyond the trough 16, the ridge 20 in the butt of which engages the cannelured neck 22^A in the cartridge 22.

The operation of the forms of my shooting practice dummy gun shown in Figures 1 and 2 is performed by grasping the stop-knob 12 and pulling the hammer plunger

rod 3 straight back, compressing the hammer plunger rod spring 11 until the hammer plunger 9 is engaged by the elevated nose 21 of the trigger 4, actuated by the trigger spring 13, the barrel core rod 2, actuated by its retracting spring 10, following the hammer plunger 9 back until it abuts the forward edge of the trigger nose 21. Aim is then taken at a target, over the foresight in part 5 through the peepsight in part 6, and the trigger 4 pressed, releasing the hammer plunger 9 against the butt 8 of the barrel core rod (which may be solid or troughed as stated) with the force of the firing spring 11, thus driving the barrel core rod 2 forward through the barrel and the stop bushing 7 until the compression of the retracting spring 10 impels its return to normal position in the gun body 1.

If the form of my shooting practice dummy gun shown in Figure 2 be used and it be desired to simulate the loading action in connection with the aiming practice, a dummy cartridge 22 is inserted through the cartridge loading aperture 16^A in the gun body 1 into the trough 16 of the barrel core rod butt 8 before cocking, aiming and firing action. When the gun is fired the dummy cartridge rides forward in and with the trough 16 of the barrel core rod butt 8 in which it was loaded and is automatically ejected by the retraction of the barrel core rod 2, by the gravity intercepted tripper 19 engaging the downwardly projecting tip 18 of the tilting plate 17 in the cartridge trough 16 as the trough mouth comes opposite to the loading and ejecting aperture 16^A in the gun body 1. A single dummy cartridge may be loaded in and ejected continuously, or a number of dummy cartridges used in successive loading from a cartridge belt, or pouch, as giving more realistic simulation of cartridge use.

In the more military form of my shooting practice dummy gun shown in Figure 3, the foresight-muzzleband 5 is of approximately military rifle design and the rearsight-breechstop 6 is formed with a hammer-plunger-sleeve-locking recess 29 and shoulder 26 in its base. The barrel core rod stop bushing 7 is elongated to protrude from the muzzle end of the gun body in simulation of a real rifle barrel; the hammer plunger 9 is formed as cartridge trough 16, differing from the trough construction used in Figure 2 in having both ends of the trough of full height, and the tilting plate 17 loosely secured in the bottom of same by the downwardly projecting tilting tip 18 being bent into hook form. The tilting tip in this modification rides in a recess 4^A in the trigger 4 which extends rearwardly from its nose 21 and the tip engages at the limit of its rearward travel the rear shoulder 24 of said trigger recess 4^A, thereby operating

the tilting plate 17 in the bottom of the trough 16 to eject a dummy cartridge, of any readily insertable size, through cartridge loading and ejecting aperture 16^A in the hammer plunger sleeve 27 and a registering opening in the gun body 1, when the hammer plunger 9 encased in its sleeve 27 is retracted a trifle rearward of the point at which the trigger nose 21 engages the hammer plunger 9 against advance movement. In this modification of my shooting practice dummy gun the hammer plunger 9 is mounted in an encasing sleeve 27 which has a manipulating arm 30 and a locking lug 28 at the rear end thereof disposed to engage by limited rotation the recess 29 and its shoulder 26 in the base rear side of the rear-sight-breechstop 6.

In Figure 3 the hammer plunger sleeve 27 is shown unlocked, in retracting position, with its manipulating arm raised and its cartridge loading and ejection aperture, or slot, 27^A, registering with the mouth of the cartridge trough 16 in the hammer plunger 9. The lower side of the hammer plunger sleeve 27 has in it a longitudinal slot 27^B of sufficient width to permit of the necessary rotation to lock the sleeve lug 28 in the rear-sight breechstop recess 29, rotate the sleeve body to cover the cartridge trough 16, and also allow longitudinal travel of the tilting plate tip 18 and the trough uprigting stud 25 on the under side of the cartridge trough.

The trigger 4 in this modification is elongated forwardly on account of the increased length of the hammer plunger 9; has a recess 4^A between its nose 21 and a rearward shoulder 24 adjoining its pivot 4^B; and is upwardly raised by a modified trigger spring 13, consisting of a flat spring mounted to bear against the under side of the forward elongation of the nose arm and the upper surface of a trigger guard 31, both the spring 13 and the guard 31 being held in position by gun body band 32 and its screw 32^A.

This approximately military modification of my shooting practice dummy gun, or rifle, shown in Figure 3 is operated in practically the same manner as the modification shown in Figure 2, with the exception that the hammer plunger 9 encased in its sleeve 27 is rendered rearwardly movable through the fixed rearsight-breech-stop 6 by upwardly rotating the sleeve 27 out of lug 28 engagement with recess 29 thereof, by means of its manipulating arm 30, which action also brings the cartridge loading and ejection aperture 27^A into registration with the mouth of the cartridge trough 16 and into alignment with gun body aperture 16^A; then drawing back freely the sleeve 27 encased hammer plunger 9, until the nose 21 of trigger 4 rises in front of the hammer plunger 9 to intercept its return. A dummy cartridge 22 may then, if

cartridge loading simulation is desired, be inserted in the trough 16 and the sleeve 27, by means of manipulating arm 30, advanced, against the hammer plunger rod spring 11 upon the arrested hammer plunger 9 until 70 the lug 28 on the butt of sleeve 27 can be locked with the rear-sight-breechstop 6 again by rotation of sleeve lug 28 into recess 29 in the rearsight-breechstop 6.

There are several advantages in the construction adopted in this modification of my shooting practice dummy gun, namely, the better simulation of real military rifle loading action and the possible use of dummy cartridges of any weight, because of the 80 cartridge trough being in the plunger hammer 9, to which additional weight is an advantage, whereas only light weight dummy cartridges may be used when the cartridge trough 16 is in the butt 8 of the barrel core 85 rod 2, as shown in the modification of my shooting practice dummy gun illustrated in Figure 2.

Various targetting tips may be used upon the barrel core rod 2 of my shooting practice dummy gun, according to the nature of the target. The novel flat faced head, or hammer, tip, 33, shown on the barrel core rod in Figures 1, 2, 3 and 6 is adapted for use against a target which indicates hits by 95 sound or action caused by impact. The ink pad and pencil marking tips respectively illustrated in Figures 7 and 8, a disk-like ink pad 34 being pivotally mounted at 34^A to normally press against the tip of barrel 100 core rod 2 by the head of the receded rod riding on a forked, right angular bow spring arm 35 of the ink pad 34, and 36 being a pencil lead held in a tubular holder 37 mounted on the tip of barrel core rod 2, 105 are types of rod tip shown and described in my hereinbefore mentioned original United States patent application on dummy practice rifles, which may be used in combination with my herein described improvements in shooting practice dummy rifles. I have devised a novel, improved form of ink marking projectile rod tip shown in Figure 9. It consists of an ink capsule or vial 38, of rubber or other preferably resilient material, having a perforated marking point 46 connected by capillary duct or ducts 47 with an interior cavity filled with ink, the whole being resiliently mounted on the muzzle end of the projectable barrel core 110 rod 2. The perforated target marking point 46 on the ink capsule 38 protrudes as from the center of a thick rimmed saucer in the target contacting face of the ink capsule 38, the surrounding depression 48 preventing smear marking of the target by ink spreading from the marking point 46, and the thick surrounding saucer rim, or ridge 48, protecting the point 46 by offering resistance to point crushing impact on the 115

target; these features ensure clean printing pressure of the fountain ink marking point 46 on the target. The ink feeding capillary duct, or ducts, 47, preferably in plurality as shown in Figure 9, lead from the perforated marking point 46 to the ink cavity 50 axially of the chamber and diagonally to its walls, so that, no matter what side of the cavity 46 is horizontally undermost in targetting operation, the ink will always, down to its lowest level, be in duct connection with the marking point 46. The ink cavity, or chamber, 50 of the ink capsule 38 as shown in Figure 9 is plugged at its base with a cork 44 after being filled with ink, but might be filled by the manufacturer and sealed. The ink capsule 38 as illustrated in Figure 9 is inserted in a holding cup 39 with a flanged base 39^a and a stem 41 that is seated in a well 42 in the head of the barrel core rod 2 of my shooting practice dummy gun. A retaining and guiding ferrule, or cylinder, 40, with an inward flange 45 at its forward end against which the base flange 39^a of the holder cup 39 is normally advanced by a holder cup stem compression spring 43, ensleaves the holder cup 39 and attaches it to the head of the barrel core rod 2.

My improved shooting practice dummy gun as illustrated and described herein is designed to be constructed mainly of wood, with metal or other substance used only where advisable or essential, to give weight, wearing quality, spring effect, compactness, etc.

I claim:—

1. In a new article of manufacture a shooting practice dummy drill gun comprising a gun body part having a cartridge insertion aperture, a spring retracted, longitudinally movable barrel core part, a spring hammer plunger part for giving forward impetus to said barrel core part, a cartridge trough in the hammer plunger part, and spring trigger means for arresting and releasing said spring hammer plunger part.
2. In a new article of manufacture a shooting practice dummy drill gun comprising a gun body part having a cartridge in-

sertion aperture, a spring retracted, longitudinally movable barrel core part, a spring hammer plunger part for giving forward impetus to the barrel core part, a cartridge-insertion-apertured sleeve part on said spring hammer plunger part, a cartridge trough in said spring hammer plunger part, cartridge ejecting means in said trough, means for operating said cartridge ejecting means when the mouth of said trough registers with the cartridge insertion aperture in the sleeve of the hammer plunger part and the cartridge insertion aperture in the gun body part.

3. In a shooting practice dummy gun a spring hammer part having a dummy cartridge receptacle therein.

4. In a shooting practice dummy gun a spring hammer part having a sleeve casing, a cartridge insertion slot in said sleeve casing and a dummy cartridge trough in said hammer part.

5. In a shooting practice dummy gun a limitedly projectable target striking part having an ink fountain target marking tip.

6. In a shooting practice dummy gun a limitedly projectable target striking part having a replaceable perforated ink capsule mounted in the tip thereof.

7. In a shooting practice dummy gun a limitedly projectable target striking part having a replaceable perforated ink capsule resiliently mounted in the tip thereof.

8. In a shooting practice dummy gun, a target striking part having in the tip thereof a replaceable perforated ink capsule with target marking point protected by ridge buffer means from crushing impact on the target.

9. In a shooting practice dummy gun a target striking part having in the tip thereof a resiliently mounted detachable vial or capsule of ink, having a perforated, duct-fed, buffer guarded, target marking point.

10. The combination in a shooting practice dummy drill gun of an ink fountain tipped target striker, a hammer part and a trigger part.

ROBERT EDWIN REARDON.
